UNITED STATES PATENT OFFICE.

ERNEST L. TEICH, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

CYLINDER-LOCK.

1,122,816.

Specification of Letters Patent.

Patented Dec. 29, 1914.

Application filed April 15, 1914. Serial No. 831,902.

To all whom it may concern:

Be it known that I, ERNEST L. TEICH, a citizen of the United States, residing at New Britain, Hartford county, State of Connecticut, have invented certain new and useful Improvements in Cylinder-Locks, of which the following is a full, clear, and exact description.

This invention relates to cylinder lock construction, and more particularly to a construction providing for control through a plurality of classes of keys including one certain class or key which will operate as a "shut-out" and as an "emergency" key as regards the remainder of the keys and the lock. These and other features and advantages of the invention are recited in detail in the following specification, taken in connection with the accompanying drawing forming part thereof and illustrating a preferable embodiment of the invention.

In these drawings: Figure 1 is a view in elevation of a lock of standard construction having the cylinder lock of the present invention applied thereto and coöperating with the dead bolt thereof. Fig. 2 is a longitudinal section through the cylinder lock with the plug conditioned for operation by a key of the first class. Fig. 3 is a view in elevation of the rear face of the cylinder lock and with the roll-back member detached therefrom, showing the relative arrangement and connection between the plug and inner and outer sleeves. Fig. 4 is a view in end elevation of the rear face of the cylinder lock with the outer portion of the roll-back removed showing the slot in the inner portion of the roll-back in coöperative relation with the sleeve members and connecting parts, the roll-back being in normal bolt-retracted position. Fig. 5 is a similar view in end elevation with the parts in the position assumed by them when the roll-back has been given a revolution in bolt-projecting direction by a key of the first class. Figs. 6, 7 and 8 are respectively views in elevation of the change, master and grand master keys forming what I term keys of the "first class". Fig. 9 is a view in end elevation, similar to Figs. 4 and 5, but with the parts in the position they assume when it is attempted to move the roll-back from the bolt-projected position of Fig. 5 in bolt-retracting direction and by a key of the second class. Fig. 10 is a similar view of the

parts in the position they assume when the roll-back has been moved to bolt-projected position by a key of the second class from the retracted position of Fig. 4. Figs. 11 and 12 are views in elevation of the "display", and grand master "display" keys forming what I term keys of the "second class". Fig. 13 is a view similar to Figs. 9 and 10 but with the parts in the position they assume when it is attempted to move the roll-back from the projected position of Fig. 10 to retracted position with a key of the first class. Fig. 14 is a view in elevation of what I term an "emergency" key forming a key of the "third class".

In the drawings I have illustrated a standard type of mortise lock mechanism with which the cylinder lock may coöperate, the necessary elements for coöperation being merely the dead bolt with its tumbler mechanism which is to be operated by the roll-back of the cylinder lock.

1 designates the lock case, 2 the face plate and 3 the cover plate of the lock case.

4 designates the usual latch bolt controlled through a knob spindle, the hub 5 of a knob spindle being shown.

6 designates a dead bolt of usual construction having a notched upper edge 7 and carrying the pivoted tumbler 8 gated at 9 to coöperate with the fence 10 of the lock case in the usual manner. This tumbler has at its rear end the usual operating offset 11 extending within the notch 7 of the dead bolt and in the path of rotation of the roll-back of the cylinder lock. In the form illustrated in the drawings, the tumbler 8 is provided with a depending tail portion 12 positioned to coöperate with the cam end 13 of the thumb turn hub, this hub having roll-back arms 14 designed to engage in a notch 15 in the lower edge of the dead bolt 6 to project and retract the dead bolt from the inner side of the door, as is usual in locks of this class.

The cylinder lock mechanism of the present invention coöperates with such a standard form of dead bolt mechanism by first engaging the offset 11 of the tumbler in the usual manner, depressing it to free it from the fence 10, and then engaging the edge of the dead bolt to project the dead bolt, the gate 9 of the tumbler engaging with the opposite edge of the fence 10 and holding the bolt against retraction until the roll-back

of the cylinder lock has been operated in a reverse direction. For the purposes of the present invention the operation of the bolt by the thumb turn need not be considered. My improved form of cylinder lock mechanism is designed to obviate the necessity of providing the ordinary lock mechanism with complicated shut-out and dead locking features necessitating an enlargement of the size of the lock mechanism and of its casing, and itself embodies and contains the blocking and shut-out mechanism which heretofore has been arranged within the lock case itself. In describing the operation of this lock, I am referring to projecting movement of the roll-back and retracting movement of the roll-back thereof as associated with such standard type of dead bolt mechanism as the dead bolt 6 and tumbler 8 with their associated parts. Projecting movement of the roll-back, therefore, means a revolution of the roll-back in a clockwise direction, and retracting movement of the roll-back is in a counter-clockwise direction.

The cylinder lock may comprise the usual casing 16 which is provided with an eccentric bore to receive the plug 17 having the usual keyhole slot therein, the end of this plug extending beyond the rear face of the casing 16 and being shaped to receive the roll-back as usual. Concentric with the plug 17 is a short inner sleeve 18, preferably positioned wholly within the ends of the casing. A second and concentric or outer sleeve 19 incloses the first or inner sleeve 18 and the plug 17 and also is positioned preferably within the ends of the casing.

19^b designates the usual master sleeve. All of these sleeves and the plug are bored to receive a plurality of spring pressed pin tumblers 20 of usual construction, these tumblers and their springs being mounted in suitable bores formed in the casing 16. The keys of the "first class", such as the guest or change key 21; the master or maid's key 22, and the grand master or house-keeper's key 23 are so bitted that when inserted, they will move the pin tumblers 20 upwardly in their bores so that these tumblers will "break" on the line between the plug 17 and the two sleeves 18 and 19^b, and so that the plug 17 alone may be turned by the inserted key 21 of the first class. The keys of the "second class", such as the display key 24 and the grand master display key 25 are so bitted that when inserted in the keyhole slot, they will position the tumblers 20 so that they will "break" on the line between the inner and outer sleeves 18-19 and so that the plug 17 and inner sleeve 18 may be turned together by the inserted key 24 of the second class. The keys of the "third class", such as the emergency key 26 are so bitted that when inserted in the

key hole slot of the plug 17, they will position the tumblers 20 to "break" on the line between the casing 16 and the outer edge of the two sleeves 19 and 19^b so that when the emergency key 26 is inserted and turned, the plug 17 and the inner and outer sleeves 18-19-19^b will be turned as one.

The rear ends of the inner and outer sleeves 18-19 are positioned within the plane of the rear face of the casing 16. The inner sleeve 18 carries a pin 18^a and the outer sleeve 19 carries a similar pin 19^a spaced radially therefrom both of these pins projecting into the clearance space at the rear face of the casing, and there being clearance between these two pins so that one sleeve and its pin may rotate relative to and past the other sleeve and its pin. The outer faces of these pins lie preferably within the plane of a boss 16^a formed on the rear face of the cylinder casing 16 serving as a bearing for the roll-backs, as will be later seen. That portion of the plug 17 within the plane of the pins 18^a and 19^a retains its cylindrical form. Within the clearance space or plane of the pins 18^a and 19^a and guiding upon the inner periphery of the casing 16 and the outer periphery of the plug 17 is a sliding block or coupling member 27, this block spanning the inner and outer sleeves 18-19 and having extending outwardly from its rear face and beyond the plane of the sleeve pins and of the boss 16^a, a pin 28.

The roll-back member of the cylinder lock is for convenience made in two portions or sections. The inner section 29 is shaped to fit over the cut-away end of the plug and bears against the boss 16^a of the casing, this section having the usual cam arm 30 and being provided with an arcuate slot 31 therein, the arc of the slot being substantially co-incident with the arc of the outer sleeve 19, and the arc of the slot being substantially less than a semi-circle. The pin 28 of the coupling member extends out into the plane of this slot 31 so that when the roll-back is rotated a sufficient distance, the portion of the roll-back at the ends of the slot will engage with the pin 28 and will then move the coupling member 27 around with the roll-back. The outer section 32 of the roll-back corresponds in contour to the inner section 29 and fits over the end of the plug 17 in the same manner, these two sections being secured together and to the plug as by the screws shown. They form in effect a single roll-back member having a groove in its rear face, the end walls of the groove co-operating with the pin 28 of the coupling member. It will be evident that when the plug 17 is rotated, the coupling member will be caught up by the roll-back at the end of the slot 31 and will be turned with the roll-back until it strikes against either one of the sleeve pins and arrests further movement of the

roll-back member. When the inner sleeve is coupled to the plug, the two rotate together and the pin of the outer sleeve will form a stop abutment, and when the plug itself is alone rotated, the coupling member 5 cooperates with the pins of both sleeves. By providing the abutments afforded by the stop pins of the inner and outer sleeves in conjunction with a blocking member which 10 is picked up by the roll-back whenever the plug is rotated, I am enabled to provide a control by a plurality of classes or series of keys, these classes corresponding in number to the number of rotatable elements embodied in the plug 17 and the inner and 15 outer sleeves 18 and 19. A key of one class is superior to a key of another or inferior class and serves as a "lock-out" key against such inferior class as well as an emergency 20 key with respect to said inferior class when the parts have been moved to bolt projected position through a key of such inferior class. The parts so cooperate, however, that when the plug and roll-back have been moved to 25 projected position by a key of the first two classes, they must be returned to retracted position by a key of that class before these parts may be again moved to projected and retracted positions by a key of the other 30 class. A key of the third class is an emergency key as to the first and second class keys and can operate the parts to projected and retracted positions notwithstanding their previous projected positions by a key 35 of one of the first two classes. If, however, the parts have first been moved to projected position by a key of the third class, the subsequent operation of these parts by keys of the first and second classes is absolutely 40 blocked, the key of the third class operating as an absolute "shut-out" key. And, before the plug and roll-back may be again operated by keys of the first and second classes, these parts must be returned to re- 45 tracted position by a key of said third class.

I will now describe in detail the operation of the roll-back with the plug and sleeves in connection with the keys of the various classes.

50 The normal relation of the parts in bolt retracted position is shown in Figs. 3 and 4. At the outset it must be understood that projecting movement of the roll-back and its associated parts is in a clockwise direction, and that retracting movement is in a counter-clockwise direction. In Fig. 4 it will be seen that the pin 28 of the coupling member lies closely adjacent one extremity of the slot 31 of the roll-back and that the 55 coupling member abuts the pin 19^a of the outer sleeve. Retracting movement of the roll-back independent of this third sleeve (and, therefore, through the keys of the first and second classes) is impossible as the pin 60 19^a blocks movement in retracting direc-

tion of the coupling member 27 and as this coupling member must perform rotate with the plug alone through a key of the first class or with the plug and inner sleeve when rotated together by a key of the second class. 70 Assuming that one of the keys 21, 22, 23 of the first class is inserted in the keyhole slot of the plug with the parts as shown in Fig. 4 and the roll-back 30 then moved in a clockwise direction for a full revolution to 75 place the parts in bolt-projected position: The end of the slot 31, removed from the pin 28 in Fig. 4, will engage with said pin at the end of an arc of movement corresponding to the arc of the slot and from 80 that point on will move the pin and its block 27 around with the roll-back and until this coupling block engages with the pin 18^a on the inner sleeve, it being understood, of course, that the inner sleeve 18 and outer 85 sleeve 19 are stationary when keys of the first class are moved. This will position the parts as shown in Fig. 5 of the drawings. If the parts are returned to bolt retracted position by a key of this same class, 90 the reverse operation will take place, the parts moving from the position shown in Fig. 5 to that shown in Fig. 4, the end of the slot 31 removed from the pin 28 in Fig. 5 picking up said pin and its coupling block 95 27 and moving said block around to abut against the pin 19^a of the outer sleeve, stopping the parts in the position shown in Fig. 4 so that the key may be withdrawn. If, 100 however, with the parts in the bolt projected position of Fig. 5 (the parts being so moved by a key of the first class), it is attempted to return the parts to bolt retracted position by a key of the second class, it will be found that while the roll-back may 105 be moved sufficiently far to retract the bolt, it may not be given a complete revolution so that the key may be withdrawn. This will enable a key of the second class to retract the bolt in an emergency and permit the 110 door to be opened, but the key of the second class may not be withdrawn from the slot with the plug and roll-back in bolt retracted position. The position of the parts when so moved by a key of the second class is 115 shown in Fig. 9 of the drawings. When such a key is inserted in the keyhole slot of the plug with the parts as shown in Fig. 5 and the plug and inner sleeve 18 together with the roll-back are turned, the pin 18^a being positioned against the coupling block 27, will at once pick up said block and carry it around with the roll-back until said block engages the pin 19^a of the outer sleeve. This 120 will permit a sufficient rotation of the cam arm of the roll-back to retract the dead-bolt but prevents the complete revolution of the plug and of the roll-back which is necessary to permit the withdrawal of the key from the slot, as will be evident; therefore, even 125 130

if the key of the second class is used as an emergency key to obtain temporary access to a room, said key must be operated to return the parts from the position shown in Fig. 9 to that shown in Fig. 5 in order that it may be withdrawn from the lock. The relative movement of these parts during this operation will be evident.

Before the parts may be moved to bolt 10 retracted and projected positions by a key of the second class, these parts must be returned from the position shown in Fig. 5 to that shown in Fig. 4 by a key of the first class as heretofore described. A key of the 15 second class may then be inserted and turned, the plug and inner sleeve with its pin 18^a moving together and the pin 18^a picking up the coupling block 27 after a short relative free movement and bringing 20 the edge of said block against the opposite side of the pin 19^a of the outer sleeve or from the position shown in Fig. 4 to that shown in Fig. 10. In this position of the parts, the roll-back is in bolt projected position and the key of the second class may be 25 withdrawn. With the parts in bolt projected position through this key they may not be returned to retracted position through a key of the first class inasmuch as the coupling block is held between the pins 18^a and 19^a of the inner and outer sleeves which do not rotate, and inasmuch as the end of the slot 31 will engage with the pin 28 after a very short amount of movement and will 30 be stopped by this pin 28 which forms a fixed abutment, the parts assuming the position shown in Fig. 13 of the drawings. The movement of the parts into projected position by means of a key of the second class 35 will, therefore, "shut out" the retraction of the parts from this position by a key of an inferior class, namely, the first class, and it will be evident that the key of the first class must be reversely moved to bring the 40 parts from the position shown in Fig. 13 back to the position shown in Fig. 10, whereupon the key of the first class may be withdrawn, leaving the parts in the bolt projected position they assume when actuated 45 by a key of the second class. A key of the second class must now be used to move the parts from the position shown in Fig. 10 to that shown in Fig. 4 before the lock is conditioned for bolt projecting and retracting 50 movement by a key of the first class.

A key of the third class, which is of the type commonly known as an "emergency" key, forms in effect both a supreme "emergency" and "shut out" key, and when inserted in the keyhole slot will cause the plug 17 and inner and outer sleeves 18-19-19^b to rotate in unison, thereby maintaining the parts always in the position shown in Fig. 4. As under these conditions 55 there can be no relative movement between

the slotted roll-back, the coupling member and the stop pins of the sleeves, it will be evident that the roll-back may be moved to projected or retracted position freely through a key of this third class irrespective of its previous position and of the class of the key which had placed it in such position. If the parts are moved from the normal bolt retracted position of Fig. 4 by a key of this third class and into bolt projected position, the parts remain in the same position and relation at the end of the projecting movement and will be in the position shown in Fig. 4. In this bolt projected position by a key of the third class, the parts are absolutely "shut out" against return to retracted position through keys of the first and second classes. For instance, the coupling member 27 engages the pin 19^a of the outer sleeve, and if the roll back and plug 80 are moved by a key of the first class, the adjacent end of the slot 31 will engage the pin 28 and block movement of the roll-back in retracting direction. So also if a key of the second class is inserted and the plug and necessary sleeve rotated together, the same blocking action will take place. The parts must be returned by a key of the "third class" to the normal bolt retracted position shown in Fig. 4 to retract the bolt before 85 they can be moved in a clockwise direction by keys of the first and second classes to move the parts to bolt projected position, as 90 heretofore described.

When the roll-back and its associated parts have been moved to bolt projected position by a key of either the first or second classes and a key of the third class is used to move the parts in a reverse direction to retract the bolt, the parts in the meantime retaining their relative positions and being in the bolt projected position of a key of a certain class (but with the bolt itself in retracted position), it is necessary 100 to again project the bolt by moving the roll-back and its parts in the reverse direction through this key of the third class. This then conditions the parts for bolt retracting movement through a key of the class by which they were originally moved to projected position. Then the parts are conditioned for operation by keys of either the first or second classes, it being understood 105 that a key of the third class is operative for bolt projection or retraction under all conditions of use of the parts by keys of the first and second classes.

Such a cylinder lock construction as I have heretofore described may be advantageously utilized with almost any standard form of lock employing a dead bolt, and makes necessary only the employment of a simple form of dead bolt mechanism while giving an extremely wide range of control 115 through the construction of the cylinder lock 120 125 130

itself, minimizing the number of parts and the size of the lock case. A practical use of the cylinder lock may be seen in the case of an ordinary hotel mortise lock such as shown in the drawings. The guest may leave the room and project the dead bolt through his change key 21, the latter being a key of the first class. Under these conditions, the maid or housekeeper holding keys 22 and 23 respectively may retract the bolt and enter the room to perform their necessary duties, their keys being likewise keys of the first class. In the event of emergency, the keys of the second class could be utilized to retract the bolt when it had been previously projected by the guest on leaving the room, although in this last case these keys of the second class could not be withdrawn from the lock until the door had been closed and the bolt again projected to leave the roll-back and its parts in the position they occupied when the guest withdrew his key. The guest, should he have valuable goods on display in the room, could, by means of a display key, lock his door upon leaving and "shut out" entrance to the room by the maid or housekeeper through their keys of the first class, as has been heretofore pointed out in detail. The grand master display key, which would be retained by the proprietor or in the office, would, of course, give access to the room, as would the emergency key, which is effective at all times. In the specific form of lock shown in the drawings, the dead bolt may be projected from the interior by means of the thumb turn. In such an event, the bolt would be in projected position with the roll-back, plug and associated parts in the normal retracted position shown in Fig. 4 of the drawings. Under these conditions the bolt could not be retracted by keys of either the first or second classes as heretofore explained, but could be retracted by means of the emergency key, which can rotate the roll-back in a counter-clockwise direction to retract the bolt. Therefore, should a guest lock himself in, he is safe from intrusion from the outside through keys of the first and second classes, but not through keys of the third class which are utilized in the event of emergency, as suicide or sickness, to gain access to a room when the dead bolt has been projected from the inside. So, also, as heretofore explained, a key of the third class may be used to project the bolt and absolutely "shut out" the apartment from access through keys of the first and second classes.

I have herein explained a specific form of cylinder lock mechanism and also a particular type of dead bolt mechanism with which it may coöperate. I desire it understood, however, that the cylinder lock is not limited to use with any particular form or dead bolt

mechanism and that the invention itself is not limited to the specific embodiment of cylinder lock construction illustrated in the drawings, but may be modified in structure and in relative arrangement of parts within the spirit of the invention as defined by the appended claims.

What I claim, therefore, and desire to secure by Letters Patent is:

1. In a cylinder lock, a rotatable plug, a roll-back member operatively connected therewith and rotated thereby, means operable by a certain key for rotating said plug and roll-back through one operating cycle, and means operable by an other certain key for subsequently rotating said parts through a reverse cycle with means for blocking the subsequent rotation of said parts through the first named cycle and by the first named certain key.

2. In a cylinder lock, a rotatable plug, a roll-back member operatively connected therewith and rotated thereby, means operable by a certain key for rotating said plug and roll-back through one operating cycle, and means operable by an other certain key for subsequently rotating said parts through a reverse cycle with means for blocking the subsequent rotation of said parts through the first named cycle and by the first named certain key, said blocking means being rendered inoperative by the subsequent and reverse movement of said parts through the first named cycle and by the second named certain key.

3. In a cylinder lock, a rotatable plug, a roll-back member operatively connected therewith and rotated thereby, means operable by a certain key for rotating said plug and roll-back into bolt projecting and retracting positions, means operable by another key for so rotating said parts with means controlled by one of said keys and operative, when said plug and roll-back have been previously moved to bolt projecting position by said key, to block subsequent movement of said plug and roll-back to retracting position by the other of said keys, said blocking means being rendered inoperative upon the subsequent movement of said parts back to retracting position by the aforesaid one of said keys.

4. In a cylinder lock, a rotatable plug, a roll-back member operatively connected therewith and rotated thereby, means operable by at least three different keys for rotating said plug and roll-back through an operating cycle and including means operable by a certain key for rotating said parts to a bolt projecting position and for blocking their subsequent movement to bolt retracting position through an other certain of said keys, said blocking means being controlled by one of said two certain keys and operative, when said parts have been moved to

said projecting position by said key, to block subsequent movement of said parts to re-tracting position by the other certain key, said blocking means being rendered inoperative upon the subsequent return of said parts to projecting position by the first mentioned certain key.

5. In a cylinder lock, a rotatable plug, a roll-back member operatively connected therewith and rotated thereby, means operable by at least three different keys for rotating said plug and roll-back through an operating cycle and including means operable by a certain key for rotating said parts 10 to a bolt projecting position and for blocking their subsequent movement to bolt re-tracting position through an other certain of said keys, said means being also operable by said first mentioned key to move said 15 parts to bolt re-tracting position when previously moved to said bolt projecting position by said other certain key, said blocking means being controlled by one of said two certain keys and operative, when said parts 20 have been moved to said projecting position by said key to block subsequent movement of said parts to re-tracting position by the other certain key, said blocking means being rendered inoperative upon the subsequent re- 25 turn of said parts to projecting position by the first mentioned certain key.

6. In a cylinder lock, a rotatable plug, a roll-back member connected therewith and rotated thereby, means operable by a key of one of at least three classes for rotating said 30 plug and roll-back through one operating cycle, and means operable by a key of another of said classes for so rotating said parts and for rotating said parts through a 35 second and reverse cycle when previously moved through said first named cycle by a key of the first named class and including means for blocking the subsequent return of said parts through the first named cycle by a key of the first named class, said blocking 40 means being rendered inoperative by the subsequent return of said parts through the first mentioned cycle by a key of the second mentioned class.

50 7. In a cylinder lock, a rotatable plug, a roll-back member operatively connected therewith and rotated thereby, operating means operable by a key of one class for rotating said plug and roll-back into bolt projecting and re-tracting positions, operating 55 means operable by a key of a second class for so rotating said parts, said last named operating means including blocking means arranged, when said parts have been first 60 moved to projecting position by a key of said second class, to block subsequent return of said parts to re-tracting position by a key of said first class, said blocking means being rendered inoperative as to keys of said first 65 class by the return of said parts to projecting

position by a key of said second class, said last named operating means, when said parts have been previously moved to projecting position by a key of said first class, being operable by a key of said second class to 70 move said parts back to re-tracting position.

8. In a cylinder lock, a rotatable plug, a roll-back member operatively connected therewith and rotated thereby, means operable by a key of one class for rotating 75 said plug and roll-back into bolt projecting and re-tracting positions, means operable respectively by keys of second and third classes for so rotating said plug and roll-back, the means operable by the key of said 80 second class, when operated to move the plug and roll-back to bolt projecting position, blocking the retraction of said parts to bolt re-tracting position through the means operable by said key of said first class, said 85 means being in turn operable by said key of said second class to retract said plug and roll-back from bolt projecting position when said parts have previously been moved to said position by a key of said first class. 90

9. In a cylinder lock, a rotatable plug, a roll-back member operatively connected therewith and rotated thereby, means operable by a key or one class for rotating said plug and roll-back into bolt projecting and 95 re-tracting positions, means operable respectively by keys of second and third classes for so rotating said plug and roll-back, the means operable by the key of said second class, when operated to move the plug and roll-back to bolt projecting position, blocking the retraction of said parts to bolt re-tracting position through the means operable by said key of said first class, said first mentioned means being in turn operable by said 100 key of said second class to retract said plug and roll-back from bolt projecting position when said parts have previously been moved to said position by a key of said first class, and a key of said third class being operable 105 to retract said plug and roll-back from bolt projecting position when said parts have been so positioned by keys of said first or second classes, and being operable to block retraction of said plug and roll-back from 110 bolt projecting position by keys of said first or second class when said parts have been moved to bolt projecting position by a key of said third class. 115

10. In a cylinder lock, a rotatable plug, a 120 roll-back operatively connected therewith and rotated thereby, means operable respectively by keys of first, second and third classes respectively for rotating said plug and roll-back into bolt projecting and re-tracting positions, the operating means controlled by the keys of the second and third classes being arranged to block bolt re-tracting movement of said plug and roll-back by a key of the first class when said parts have 125 130

been moved to bolt projecting position by a key of a second or third class.

11. In a cylinder lock, a rotatable plug, a roll-back operatively connected therewith and rotated thereby, means operable respectively by keys of first, second and third classes for rotating said plug and roll-back into bolt projecting and retracting positions, the operating means controlled by the keys of the second and third classes being arranged to block bolt retracting movement of said plug and roll-back by a key of the first class when said parts have been moved to bolt projecting position by a key of a second or third class, and said operating means, controlled by the keys of second and third classes respectively, being arranged to move said plug and roll back to bolt retracting position when said parts have been moved to bolt projecting position by keys of said first and second classes respectively.

12. In a cylinder lock, a rotatable plug, a roll-back operatively connected therewith and rotated thereby, means operable respectively by keys of first, second and third classes for rotating said plug and roll-back into bolt projecting and retracting positions, the operating means controlled by the keys of the second and third classes being arranged to block bolt retracting movement of said plug and roll-back by a key of the first class when said parts have been moved to bolt projecting position by a key of a second or third class, and said operating means controlled by the keys of second and third classes respectively, being arranged to move said plug and roll-back to bolt retracting position when said parts have been moved to bolt projecting position by keys of said first and second classes respectively, the operating means controlled by a key of said third class, when actuated by a key of that class to position the plug and roll-back in projecting position, being arranged to block the return of said parts to retracting position through keys of said first and second classes.

13. In a cylinder lock, a casing, a rotatable plug therein having a keyhole slot, pin tumbler mechanism coöperating with said plug, a roll-back member carried by and rotatable with said plug, a sleeve member within said casing inclosing said plug, said tumbler mechanism coöperating with said sleeve member and said plug, a rigid abutment carried by said sleeve member, a movable connecting abutment interposed between said sleeve abutment and said roll-back member, said roll-back and said connector member having a lost motion connection therebetween, said plug and roll-back being rotatable independently of said sleeve by a certain key coöperating with said tumbler mechanism to move said roll-back and

connector block in the direction of said fixed sleeve abutment, and another key being arranged to rotate said plug, roll-back and sleeve in unison.

14. In a cylinder lock, a casing, a rotatable plug therein, inner and outer sleeve members inclosing said plug, pin tumbler mechanism coöperating with said sleeve members and with said plug, said tumbler mechanism being operable by keys of different classes to permit the independent rotation of said sleeve members and the rotation of said plug independently of said sleeve members, annularly spaced fixed abutment members carried by said sleeves arranged to rotate in concentric arcs, with a clearance space therebetween, a coupling member rotatable about said plug in the plane of said sleeve abutments and bridging the arcuate space therebetween, a roll-back carried by said plug and rotating therewith and having a lost motion connection with said connector block.

15. In a cylinder lock, a casing, a rotatable plug therein, inner and outer sleeve members inclosing said plug, pin tumbler mechanism coöperating with said sleeve members and with said plug, said tumbler mechanism being operable by keys of different classes to permit the independent rotation of said sleeve members and the rotation of said plug independently of said sleeve members, annularly spaced fixed abutment members carried by said sleeves arranged to rotate in concentric arcs with a clearance space therebetween, a coupling member rotatable about said plug in the plane of said sleeve abutments and bridging the arcuate space therebetween, a roll-back member connected to and rotating with said plug, and a pin and slot connection between said connector member and said roll-back member permitting limited free movement between the roll-back and the connector member, said roll-back moving said connector member against the fixed abutment formed by one of said sleeve studs when said plug or said plug and said inner sleeve member are rotated.

16. In a cylinder lock, a rotatable plug, a roll-back element in operative connection therewith and rotated thereby, key-controlled means coöperating with said plug formed and arranged for a complete revolution of said plug to one operating cycle of said roll-back, said means being controlled and operable by keys of each of two different classes to rotate said plug through a complete revolution in opposite directions.

17. In a cylinder lock, a rotatable plug, a roll-back element in operative connection therewith and rotated thereby, key-controlled means coöperating with said plug formed and arranged for a complete revo-

lution of said plug to one operating cycle of said roll-back, said means being controlled and operable by keys of each of two different classes to rotate said plug through a complete revolution in opposite directions, the means controlled by a key of one of said classes being arranged, when operated for one cycle, to block the operation of said plug and roll-back in the opposite direction for 30 the reverse cycle through a key of the other of said classes.

18. In a cylinder lock, a rotatable plug, a roll-back element in operative connection therewith and rotated thereby, key-controlled means coöperating with said plug formed and arranged for a complete revolution of said plug to one operating cycle of said roll-back, said means being controlled and operable by keys of each of two different classes to rotate said plug through 20 a complete revolution in opposite directions, said means, when operated by a key of one class to give a complete revolution to said plug in one direction, being only operable for a complete revolution in the reverse direction by a key of the same class.

19. In a cylinder lock, a rotatable plug, a roll-back element in operative connection therewith and rotated thereby, key-controlled means coöperating with said plug formed and arranged for a complete revolution of said plug to one operating cycle of said roll-back, said means being controlled and operable by keys of each of two different classes to rotate said plug through a complete revolution in opposite directions, said means, when operated by a key of one class to give a complete revolution to said plug in one direction, being only operable 40 for a complete revolution in the reverse direction by a key of the same class, the means controlled by a key of one of said classes being arranged, when operated to rotate said plug for one cycle of the roll-back, to block 50 the operation of said plug and roll-back for the reverse cycle through a key of the other of said classes.

20. In a cylinder lock, a rotatable plug, a roll-back element in operative connection therewith and rotated thereby, key-controlled means coöperating with said plug constructed and arranged for a complete revolution of said plug to one operating cycle of said roll-back, said means being controlled and operable by keys of each of three different classes to rotate said plug through a complete revolution, said means, when operated by a key of each of two of 55 said classes to give a complete revolution to said plug in one direction, being arranged to block the operation of said plug by a key of the other of said classes for a complete revolution in the reverse direction.

21. In a cylinder lock, a rotatable plug, a roll-back element in operative connection

therewith and rotated thereby, key-controlled means coöperating with said plug constructed and arranged for a complete revolution of said plug to one operating cycle of said roll-back, said means being controlled and operable by keys of each of three different classes to rotate said plug through a complete revolution, said means, when operated by a key of one certain of 70 said classes to give a complete revolution to 75 said plug in one direction, being arranged to block the operation of said plug by keys of the other two classes in the reverse direction of rotation.

22. In a cylinder lock, a rotatable plug, a roll-back element in operative connection therewith and rotated thereby, key-controlled means coöperating with said plug constructed and arranged for a complete revolution of said plug to one operating 80 cycle of said roll-back, said means being controlled and operable by keys of each of three different classes to rotate said plug through a complete revolution, the means controlled by a key of the first of said 85 classes, when operated by a key of said first class for a full revolution in one direction, being arranged to block the operation of said plug for a complete revolution in the 90 reverse direction by a key of the second of said classes, said means being arranged to permit complete rotation in said reverse direction by a key of the third of said classes and to permit unrestricted and complete rotation in both directions by a key of said 95 third class.

23. In a cylinder lock, a rotatable plug having a key-hole slot therein, inner and outer sleeves coöperating with said plug, a roll-back carried by and rotating with said 105 plug, pin tumbler mechanism coöperating with said plug and said sleeves and with three classes of keys, said plug being rotatable by keys of each of said three classes, said inner and outer sleeves being respectively 110 coupled to and rotated with said plug by keys of second and third classes.

24. In a cylinder lock, a rotatable plug, a roll-back operatively connected therewith and rotated thereby, means operable respectively by keys of first, second and third classes for rotating said plug through a complete revolution in opposite directions into bolt projecting and retracting positions respectively, the operating means controlled 115 by keys of the second and third classes, when said plug has been rotated a complete revolution to bolt projected position by a key of 120 said second or third class, being arranged to block said plug against complete rotation in 125 the reverse direction by a key of said first class.

25. In a cylinder lock, a rotatable plug having a key-hole slot therein, inner and outer sleeves coöperating with said plug, a 130

roll-back carried by and rotating with said plug, pin tumbler mechanism coöperating with said plug and said sleeves and with three classes of keys, said plug being rotated through a complete revolution to one operating cycle of said roll-back by keys of each of said three classes, said inner and outer sleeves being respectively coupled to

and rotated with said plug by keys of the second and third classes, and a lost motion connection between each of said sleeves and said roll-back. 10
